UNITED STATES PATENT OFFICE.

CLAUDE M. FAUST, OF CHICAGO, ILLINOIS, ASSIGNOR OF ONE-THIRD TO JOHN W. TALBOT, OF CHICAGO, ILLINOIS.

ROLLER SKATE.

Application filed October 12, 1925. Serial No. 31,969.

My invention relates to roller skates and particularly to the class of skates known as rink skates which are used by professional skaters for high speed and exhibit skating.

One of the objects of my invention is to provide a cheap, simple and efficient form of roller skate, which, by the elimination of unnecessary parts will include only those parts absolutely necessary for the proper functioning of the skate and limit the number of parts which are liable to get out of order and which will therefore be a skate which will give the skater the fullest amount of pleasure with the elimination of many dangers attendant upon the roller skates as now manufactured and sold.

Another object of my invention is to provide a roller skate which will permit the body of the skater to assume any angular position, while the four rollers on the skate will always maintain a contact with the floor of the rink. This positive action caused by the weight of the skater upon the foot plate of the skate and which will tend to place the footplate in an angular position will always adjust itself when the foot is lifted from the floor or the inclination of the body changes to an upright position by means of the recoil mechanism hereinafter described.

A still further object of my invention is to combine the several different parts of the skate, eliminating casting, and insuring strength and durability, by making the combined structure by drop forging, so that the number of cooperating parts will be materially decreased.

Still another object of my invention is to eliminate a resilient member such as rubber, etc., which in time deteriorate and become unsuitable for the purpose for which they are intended, by replacing the same with a spring which is so mounted as to always cause the footplate to return to a position parallel with the floor regardless of the position it has been caused to assume by the skater. It is a well known fact that when rubber resilient means has been used for returning the footplate of the skate to its original position after being angularly depressed by the skater, the rubber loses a great part of its resiliency and the footplate will, after a short usage, refuse to return to the position parallel with the floor. This, of course, is caused by a weighty skater taking all the

life out of one side of the rubber resilient part, so that one cannot hope to maintain the relative positions between the foot plate and the rollers.

In my invention I use a coil spring which is never bent to a point near the modulus of elasticity so that the recoil of the spring is so positive that regardless of the weight of the skater the footplate will always return to its original position with relation to the rollers of the skate.

Other objects and advantages of my invention will be readily appreciated as the same becomes better understood by reference to the following description when considered in connection with the accompanying drawing, in which,

Fig. 1 is a side elevation of my improved skate showing the rear carrier means and its cooperative elements in section,

Fig. 2 is a bottom plan view of the same, Fig. 3 is a perspective view of my improved roller skate showing the footplate deflected as would be its condition during a right handed turn,

Fig. 4 is a cross sectional view on the line 4-4 of Fig. 3 and looking in the direction of the arrows, and

Fig. 5 is a cross sectional view of my improved skate taken on the line 5-5 of Fig. 1.

Like symbols of reference herein indicate like parts in each of the figures of the drawing.

As illustrated in the drawing, my improved roller skate has the ordinary footplate 6 extending across the top of the same for forming a resting place for the foot of the skater and is provided at the rear end thereof with a pair of upwardly extending wings 7 for limiting the position of the heel which have the usual holes 8 through the same for permitting a strap 10 to be passed therethrough for buckling around the instep of the skater. At a point near the front of the footplate, the same is provided with a pair of clamping members 9 connected by means of a right and left hand threaded screw 11, and these clamping members extend through the dovetailed recesses 12 in the lugs 13, while an upright forked portion 14 is adapted to position the screw between said lugs and prevent any longitudinal movement of the screw therein. Each of the clamping members have inclined faces 15 for engaging in the recesses in the

lugs 13 and have a downwardly projecting member 16 which is threaded and adapted to cooperate with the threads on the opposite ends of the screw 11. The screw 11 is provided with a square portion or shank 17 at each end of the same for receiving a key (not shown) for adjusting the clamping members into any position, such as for attachment and removal from the shoe 10 of the skater.

The footplate 6 is provided with a reinforcing rib 18 which extends substantially the full length of the same and is provided at a point near the rear of the same with a small lug 19 having a recess 21 therein, as later explained. At a point slightly to the rear of the forked portion 14 is a recess 22 which will be later explained. At a point near the heel end of the footplate is 20 a downwardly extended projection commonly called a hanger 23, while another hanger 24 extends downward from that portion of the footplate 6 usually covered by the ball of the foot or immediately beyond the 25 metatarsal bones of the foot.

It has been the custom in manufacturing skates of this kind to rivet the footplate 6 to the supporting rib 18 and the heads of the rivet extending above the footplate often cause unusual calli and sore places on the foot of the wearer, and to prevent and eliminate such conditions, I form the footplate, the supporting rib, the hangers, the clamping dovetailed portions, and the fork shaped portion of one piece by drop forging, so that the entire upper part of the skate for the hanging of the rollers has no parts to come out of adjustment and this elimination of cooperating parts will prevent accidents and the laying up of the skate for repairs.

The skate is provided with two pairs of rollers 25 and 26, and in this particular instance wherein I am describing a rink skate, I prefer to use composition rollers which are light, durable, and will not discolor the skating rink on account of the lack of carbon in the same, although for street use, metal or wooden rollers may be used and my invention is not designed to include any particular material for the formation of said rollers. The rollers are provided with an axle 27 extending through each pair of same and are provided with the usual ball bearings and casings and plates for taking the end thrust, all of which is well known in the art and which I do not claim as any part of my invention except in so far as it may relate to the combination of parts herein described and claimed. That portion of the axle 27 between the inner edges of each of the pairs of wheels is provided with a supporting member 28 which has, at a position near the center of the same, an upwardly extending rib or leaf 29 which has a pivotal end 31 which fits into the recess 21 on

the footplate 6 and forms a pivotal connection therewith. At a position beyond where the leaf or rib 29 extends outwardly from the body portion 28 is a leaf or ear 32 which is provided at the center of the same with a semi-circular depression or concave portion 33, while a screw or bolt 34 is adapted to pass through a central opening 35 in the same and extend upward and into a threaded hole 36 in the rear hanger 23. This bolt 34 has the under face of its head 37 shaped to fit the concave or semi-circular portion 33 of the ear 32 and a spiral spring 38 fits immediately around the outside of the concave portion 33 and extends upwardly into a 80 spring cup 41 surrounding said bolt, while a lock nut 42 immediately at the bottom of said spring cup 41 and hanger 23 is adapted to lock the said bolt in any desired position. It will therefore be apparent that the 85 amount of tension between the footplate 6 and the roller members 26 can be very nicely adjusted by means of the slotted head 43 in the bolt 34 by adjusting the tension on the spring 38.

The spring 38 tapers towards its upper end, that is the portion lying within the spring cup 41 is smaller in diameter than that portion surrounding the semi-circular portion 33. The spring 44 cooperates with the leaf 45 and spring portion 46 connected with the hanger 47 in exactly the same manner as the corresponding parts in the rear truck of the skate, while the rib or leaf 48 has a pivotal end 49 which enters into and 100 engages with the recess 22 in order to form a pivotal connection therewith.

The operation of my improved roller skate is very easily described, as the shoe of the skater is clamped into the skate by having 105 the heel of the shoe rest against the upwardly extending wings 7 and firmly secured therein by means of the strap 10 being attached through the buckle 20 across the instep of the skater while the sole of the shoe is attached to said footplate 6 by means of turning the shank or square portion 17 of the screw 11 which causes the upwardly extending members 15' of the attaching 110 members 12 and 13 to engage by their serrated faces with the sole of the shoe and thus firmly secure the same between said attaching members. The trucks or pairs of 115 rollers 25 and 26 are pivoted through the pivotal ends 21 and 41 with their corresponding recesses so that the footplate 6 may be turned over to an angle of at least 33°, while still keeping both rollers of each truck on the floor of the rink. This is accomplished by means of the compression of the springs 38 and 44 which are depressed to one side of the same as the body of the skater inclines.

In order to prevent dislocation and breakage of parts, I have found it advisable to 130

construct the member 28, the upwardly extending leaf or rib 29, and the ear shaped portion 32 of a single piece and this can readily be accomplished by drop forging which is the most substantial method and will positively prevent the breakage of any of the parts of the combination, so that this, in combination with the foot plate and the elements composing that combination, will 10 form a skate comprising practically three major parts, that is the footplate and the two carriage or roller portions.

While I have shown and described a preferred embodiment of the invention, it should be understood that the details of construction are capable of wide modification and variation without departing from the spirit of the invention or sacrificing any of the advantages thereof. Hence, I reserve 20 all such variations and modifications and mechanical equivalents as fall within the spirit and purview of the appended claims.

I claim:

1. A roller skate having an integrally formed foot plate, a reinforcing rib, a pair of hangers and a pair of recesses near each extremity of the rib, two pairs of rollers each supported by an axle and having a carrier member comprising an upwardly extending leaf pivotally engaging one of the recesses in said rib, and an ear member having a convex center portion for supporting resilient means between the same and one of said hangers in order to permit angular displacement of said foot plate while the rollers remain in contact with the floor.

2. A roller skate having a foot supporting member, two pairs of rollers, each pair having a carrier consisting of a pivotally mounted leaf and ear member, a concave center in said ear portion, a bolt having the under side of its head convex, and resilient means between said ear and said foot member to permit angular displacement of the same.

3. A roller skate having a foot supporting member, two pairs of rollers having an axle between each pair, a carrier mounted on the axle of each pair of rollers consisting 60 of a leaf member and an ear member, said leaf having its outer end so shaped as to enter a recess and form a pivotal connection

therewith, a concave center in said ear member, a bolt having the underside of its head convex to permit it to turn universally in 55 said concave center while its other end is securely fixed in said foot member, resilient means between said foot member and said ear whereby the foot plate may adapt itself to the position of the skater while all the 60 rollers of the skate remain in contact with the floor.

4. In a roller skate of the class described, leaf members extending upward from each carriage and having a pivotal connection 65 with the foot member, an ear on each carriage having a concave center, a bolt extending through said ear and into said foot member, and resilient means between said ear and foot member whereby said foot 70 member may be angularly displaced by the inclination of the body of the skater, while the rollers remain in contact with the floor.

5. In a roller skate of the class described, leaf members extending upward from each carriage and having a pivotal connection 75 with the foot member, an ear on each carriage having a concave center, a bolt extending through said ear and into said foot member, a spring cup on said bolt, and a 80 spiral spring between said ear and said spring cup, for permitting angular displacement of said foot member while the rollers of the skate remain in contact with the floor.

6. In a roller skate of the class described, leaf members extending upward from each carriage and having a pivotal connection 85 with the foot member, an ear on each carriage having a concave center, a bolt extending through said ear and into said foot member, a spring cup on said bolt, and a 90 spiral spring between said ear and said spring cup, for permitting angular displacement of said foot member while the 95 rollers of the skate remain in contact with the floor, said spring being of sufficient tension to return the foot member to its position parallel with the floor when the angular displacement is removed.

In witness of the foregoing I affix my signature.

CLAUDE M. FAUST.
